UNITED STATES PATENT OFFICE.

CARSON DURKEE, OF VICKSBURG, MICHIGAN.

MOTOR-VEHICLE.

No. 820,709.

Specification of Letters Patent.

Patented May 15, 1906.

Application filed June 12, 1905. Serial No. 264,860.

To all whom it may concern:

Be it known that I, CARSON DURKEE, a citizen of the United States, residing at Vicksburg, county of Kalamazoo, State of Michigan, have invented certain new and useful improvements in Motor-Vehicles, of which the following is a specification.

This invention relates to improvements in motor-vehicles.

10 The objects of this invention are, first, to provide in a motor-vehicle an improved driving-gear whereby the power is delivered to all of the carrying-wheels; second, to provide an improved motor-vehicle having these 15 features which is comparatively simple and economical in structure and very strong and durable.

Further objects and objects relating to the structural details will definitely appear from 20 the detailed description to follow.

I accomplish the objects of my invention by the devices and means described in the following specification.

The invention is clearly defined, and pointed out in the claims.

A structure embodying the features of my invention is clearly illustrated in the accompanying drawings, forming a part of this specification, in which—

30 Figure 1 is a plan view of a motor-vehicle embodying the features of my invention, the body and motor not being shown. Fig. 2 is a detail longitudinal sectional view of my improved motor-vehicle, taken on a line corresponding to line 2 2 of Fig. 1. Fig. 3 is an enlarged sectional view taken on a line corresponding to line 3 3 of Fig. 1. Fig. 4 is an enlarged detail sectional view taken on a line corresponding to line 4 4 of Fig. 1. Fig. 45 5 is a detail side elevation view of one of the coupling-bars H for the axles. Fig. 6 is an enlarged cross-sectional view taken on a line corresponding to line 6 6 of Fig. 2, showing the structural details of one of the clips H' for the coupling-bars H. Fig. 7 is an enlarged detail sectional view taken on a line corresponding to line 7 7 of Fig. 2, showing the connection for the steering-rod.

In the drawings the sectional views are 50 taken looking in the direction of the little arrows at the ends of the section-lines, and similar letters of reference refer to similar parts throughout the several views.

Referring to the drawings, I provide an 55 axle-frame for both the front and rear axles.

These frames preferably consist of the longitudinal bars A and the cross-pieces or end blocks A', which are rigidly secured thereto. Axles C are provided for the wheels C''. The axles C are arranged in suitable bearings in 60 the axle-sleeves B. The wheels are fixed to the axles. The axle-sleeves are pivotally secured to the frames by the pivots B'', which are vertically arranged through the end pieces A'. (See Fig. 3.) The front and rear 65 axle-frames are connected by a reach a and by the side bars a'. The side bars a' are pivotally secured to the frames and serve, in connection with the reach, to hold them in proper relation to each other. On the inner ends of 70 the axle-sleeves B are rollers b. Yoke-like ways F are provided for these rollers. The ways F are secured on the under side of the axle-frames. This effectually supports the 75 axles and allows the free swinging thereof on the pivots B''. The ways also serve as stops to limit the movement of the axles.

A beveled gear C' is secured to each wheel C''. Beveled gears c are arranged to mesh with these gears C'. The gears c are journaled on the pivot-pins B'' of the axles, so that no matter what the position of the wheels may be the gears C' and c are always in mesh. A driving-shaft made up of sections D D is supported on suitable forwardly-projecting brackets carried by the rear axle-frame. The driving-sprocket M is connected to the driving-shaft sections by a suitable compensating-gear connection. The driving-shaft sections are provided with beveled 85 pinions B', which are arranged to mesh with the main gear D''' of the compensating gear, through which power is delivered from the driving-shaft to the wheels. Shafts D'', having pinions c' thereon, arranged to mesh with 90 the gears c, are supported in suitable bearings on the axle-frames. The rear gears d of the compensating gears are fixed upon the rear shafts D'', while the forward gears d are connected to the forward shafts D'' by the tumbling-rods E. The tumbling-rods are provided with suitable universal couplings E'. The main gear D''' of the compensating gear is connected to the gears d by suitable pinions d', arranged in the well-known manner. 100 With the parts thus arranged the power is delivered to all four of the wheels C''. With the compensating gears arranged in the connections as described the vehicle may be turned in any manner or the wheels pass 105 110

over any obstruction without skidding the wheels. It is found, however, in practice, particularly in small light vehicles, that the compensating gear in the driving-shaft connections is not essential to their practical operation.

The steering mechanism consists of a suitable steering-rod I, to which the pinion I', which is arranged to mesh with the rack I'', is secured. The steering-rod I is supported in a suitable bearing carried by the body J', which is shown in conventional form in the drawings. The rack I'' is connected to one of the rear axles by the link i. The diagonally opposite front and rear axles are connected in pairs by the links h' and sliding bars H. Each of the bars H is provided with a pair of laterally-projecting and oppositely-projecting ears h. The links h' are pivotally secured at one end to the inwardly-projecting pins b' on the inner ends of the axle-sleeves and at the other end to the laterally-projecting ears h of the connecting-bars H. The bars H are slidably secured on the under side of the reach a by the clips H', as clearly appears in Figs. 1, 2, and 6 of the drawings. Thus arranged the axles of the diagonally opposite wheels are connected to secure the proper adjustment thereof in turning. To act upon the four wheels together, the forward axles are connected by means of the pivoted bar G and the links g. The bar G is supported by the forwardly-projecting end of the reach a and the bracket G'. The bar G is connected to the axle-sleeves by means of the links g. I secure by this arrangement of parts a vehicle which is very responsive in steering and one which may be turned in a very small area. As before remarked, the shifting of the wheels in turning does not in any manner affect the driving-gear connections thereto.

By my improved driving-gear connections I am enabled to deliver power to all of the carrying-wheels, so that a maximum of traction-friction is secured for the wheels. By applying the power to all of the carrying-wheels the maximum amount thereof is utilized in propelling the load.

By constructing the parts as I have illustrated and described they are largely interchangeable, so that the cost of manufacture is greatly reduced.

While I have illustrated and described my improved driving-gear in connection with a road-vehicle, I desire to remark that it is applicable to motor-vehicles or other styles, as will be readily apparent.

I have illustrated and described my improved driving-gear for motor-vehicles in the form preferred by me on account of its structural simplicity and strength. I am, however, aware that it is capable of very considerable variation without departing from my invention.

Having thus described my invention, what I claim as new, and desire to secure by Letters Patent, is—

1. The combination of the axle-frames; a reach rigidly secured to said axle-frames; a pair of side bars pivotally secured to said axle-frames; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the axle-frames; tumbling-rods having universal-joint connections for connecting said compensating gears to the shafts carried by the forward axle-frames; a steering-rod; a pinion thereon; a rack arranged to mesh with said pinion; a link connecting said rack to one of the rear axle-sleeves; a pair of connecting-bars slidably secured to said reach; links arranged to connect the diagonally opposite axles to said bars; a pivoted bar; and links for connecting said bar to the forward axles, all coacting for the purpose specified.

2. The combination of the axle-frames; a reach rigidly secured to said axle-frames; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the axle-frames; tumbling-rods having universal-joint connections for connecting said compensating gears to the shafts carried by the forward axle-frames; a steering-rod; a pinion thereon; a rack arranged to mesh with said pinion; a link connecting said rack to one of the rear axle-sleeves; a pair of connecting-bars slidably secured to said reach; links arranged to connect the diagonally opposite axles to said bars; a pivoted bar; and links for connecting said bar to the forward axles; all coacting for the purpose specified.

3. The combination of the axle-frames; a reach; a pair of side bars pivotally secured to said axle-frames; wheels; axles therefor; sleeves in which said axles are journaled; pivots for said axle-sleeves; rollers on said

sleeves; ways for said rollers secured to said axle-frames; gears secured to said wheels; gears journaled on said axle-pivots arranged to mesh with said gears on said wheels; a section driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the axle-frames; tumbling-rods having universal-joint connections for connecting said compensating gears to the shafts carried by the forward axle-frames; a steering-rod; a pinion thereon; a rack arranged to mesh with said pinion; a link connecting said rack to one of the rear axle-sleeves; a pair of connecting-bars slidingly secured to said reach; links arranged to connect the diagonally opposite axles to said bars; a pivoted bar; and links for connecting said bar to the forward axles, all coacting for the purpose specified.

4. The combination of the axle-frames; a reach; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the axle-frames; a steering-rod; a pinion thereon; a rack arranged to mesh with said pinion; a link connecting said rack to one of the rear axle-sleeves; a pair of connecting-bars slidingly secured to said reach; links arranged to connect the diagonally opposite axles to said bars; a pivoted bar; and links for connecting said bar to the forward axles, all coacting for the purpose specified.

5. The combination of the axle-frames; a reach rigidly secured to said axle-frames; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the forward axle-frames; a pivoted bar; and links for connecting said bar to the forward axles, all coacting for the purpose specified.

6. The combination of the axle-frames; a reach; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the forward axle-frames; a steering-rod; a pinion thereon; a rack arranged to mesh with said pinion; a link connecting said rack to one of the rear axle-sleeves; a pair of connecting-bars slidingly secured to said reach; links arranged to connect the diagonally opposite axles to said bars; a pivoted bar; and links for connecting said bar to the forward axles, all coacting for the purpose specified.

7. The combination of the axle-frames; a reach; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the forward axle-frames; a steering-rod; a pinion thereon; a rack arranged to mesh with said pinion; a link connecting said rack to one of the rear axle-sleeves; a pair of connecting-bars slidingly secured to said reach; links arranged to connect the diagonally opposite axles to said bars; a pivoted bar; and links for connecting said bar to the forward axles, all coacting for the purpose specified.

8. The combination of the axle-frames; a reach rigidly secured to said axle-frames; a pair of side bars pivotally secured to said axle-frames; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the forward axle-frames; and tumbling-rods having universal-joint connections for connecting said compensating gears to the shafts carried by the forward axle-frames; for the purpose specified.

9. The combination of the axle-frames; a reach rigidly secured to said axle-frames; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving-shaft connection for said shaft-sections; shafts arranged in suitable bearings on said axle-frames; gears

- thereon arranged to drive said gears on said axle-pivots; compensating gears for connecting said driving-shaft sections to said shafts carried by the axle-frames; and tumbling-
 5 rods having universal-joint connections for connecting said compensating gears to the shafts by the forward axle-frames, all coacting for the purpose specified.
9. The combination of the axle-frames; a
 10 reach; a pair of side bars pivotally secured to said axle-frames; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections;
 15 shafts arranged in suitable bearings on said axle-frames; gears thereon arranged to drive said gears on said axle-pivots; compensating gears for connecting said driving-shaft sections to said shafts carried by the axle-frames; and tumbling-
 20 rods having universal-joint connections for connecting said compensating gears to the shafts carried by the forward axle-frames, all coacting for the purpose specified.
10. The combination of the axle-frames; a
 25 reach; wheels; axles therefor; sleeves in which said axles are journaled; pivots for said axle-sleeves; rollers on said sleeves; yoke-like ways for said rollers secured to said axle-frames; gears secured to said wheels; gears journaled on said axle-pivots arranged to mesh with said gears on said wheels; a sectional driving-shaft; a compensating-gear driving connection for said shaft-sections;
 30 shafts arranged in suitable bearings on said axle-frames; gears thereon arranged to drive said gears on said axle-pivots; compensating gears for connecting said driving-shaft sections to said shafts carried by the axle-frames; and tumbling-
 35 rods having universal-joint connections for connecting said compensating gears to the shafts carried by the forward axle-frames, all coacting for the purpose specified.
11. The combination of the axle-frames; a
 40 reach; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections;
 45 shafts arranged in suitable bearings on said axle-frames; gears thereon arranged to drive said gears on said axle-pivots; compensating gears for connecting said driving-shaft sections to said shafts carried by the axle-frames; and tumbling-
 50 rods having universal-joint connections for connecting said compensating gears to the shafts carried by the forward axle-frames, all coacting for the purpose specified.
12. The combination of the axle-frames; a
 55 reach; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts carried by the axle-frames; a steering-rod; connections therefrom to one of said rear axles; a pair of connecting-bars slidingly secured to said reach; links arranged to connect the diagonally opposite axles to said bars; a pivoted bar; and links for connecting said bar to the forward axles, all coacting for the purpose specified.

13. The combination of the axle-frames; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a compensating-gear driving connection for said shaft-sections; shafts arranged in suitable bearings on said axle-frames; gears arranged thereon to drive said gears on said axle-pivots; compensating gears for connecting said driving-shaft sections to said shafts carried by said axle-frames; tumbling-
 60 rods having universal-joint connections for connecting said compensating gears to the shafts carried by the forward axle-frames; a steering-rod; connections therefrom to one of said rear axles; means for securing the diagonally opposite axles together; a pivoted bar; and links for connecting said bar to the forward axles, all coacting for the purpose specified.
14. The combination of the axle-frames; wheels; axles therefor; sleeves in which said axles are journaled; pivots for said axle-sleeves; rollers on said sleeves; ways for said rollers secured to said axle-frames; gears secured to said wheels; gears journaled on said axle-pivots arranged to mesh with said gears on said wheels; a sectional driving-shaft; a

- compensating - gear driving connection for said shaft-sections; shafts arranged in suitable bearings on said axle-frames; gears thereon arranged to drive said gears on said axle-pivots; compensating gears for connecting said driving-shaft sections to said shafts carried by the axle-frames; and tumbling-rods 65 having universal-joint connections for connecting said compensating gears to the shafts carried by the forward axle-frames, all coacting for the purpose specified.

5 18. The combination of the axle-frames; a reach; wheels; axles therefor; sleeves in which said axles are journaled; pivots for said axle-sleeves; rollers on said sleeves; ways for said rollers secured to said axle-frames; gears secured to said wheels; gears journaled on said 70 axle-pivots arranged to mesh with said gears; on said wheels; a sectional driving-shaft, a compensating - gear driving connection for said shaft-sections; shafts arranged in suitable bearings on said axle-frames; gears 75 thereon arranged to drive said gears on said axle-pivots; and compensating gears for connecting said driving-shaft sections to said shafts carried by the axle-frames; for the purpose specified.

10 15. The combination of the axle-frames; a reach; wheels; axles therefor; sleeves in which said axles are journaled; pivots for said axle-sleeves; rollers on said sleeves; ways for said rollers secured to said axle-frames; gears secured to said wheels; gears journaled on said 80 axle-pivots arranged to mesh with said gears; on said wheels; a driving-shaft; shafts arranged in suitable bearings on said axle-frames; gears thereon arranged to drive said gears on said 85 axle-pivots; and compensating gears for connecting said driving-shaft sections to said shafts carried by the axle-frames; for the purpose specified.

15 20. The combination of the axle-frames; a reach; wheels; axles therefor; sleeves in which said axles are journaled; pivots for said axle-sleeves; rollers on said sleeves; ways for said rollers secured to said axle-frames; gears secured to said wheels; gears journaled on said 90 axle-pivots arranged to mesh with said gears on said wheels; a driving-shaft; shafts arranged in suitable bearings on said axle-frames; gears thereon arranged to drive said gears on said 95 axle-pivots; and connections from said driving-shaft sections to said shafts on said axle-frames, all coacting for the purpose specified.

25 25. The combination of the axle-frames; wheels; axles therefor; sleeves in which said axles are journaled; pivots for said axle-sleeves; rollers on said sleeves; ways for said rollers secured to said axle-frames; gears secured to said wheels; gears journaled on said 100 axle-pivots arranged to mesh with said gears on said wheels; a driving-shaft; shafts arranged in suitable bearings on said axle-frames; gears thereon arranged to drive said gears on said 105 axle-pivots; and connections from said driving-shaft sections to said shafts on said axle-frames, all coacting for the purpose specified.

30 30. The combination of the axle-frames; wheels; axles therefor; sleeves in which said axles are journaled; pivots for said axle-sleeves; rollers on said sleeves; ways for said rollers secured to said axle-frames; gears secured to said wheels; gears journaled on said 110 axle-pivots arranged to mesh with said gears on said wheels; a driving-shaft; shafts arranged in suitable bearings on said axle-frames; gears thereon arranged to drive said gears on said 115 axle-pivots; and connections from said driving-shaft sections to said shafts on said axle-frames, all coacting for the purpose specified.

35 35. The combination of the axle-frames; wheels; axles therefor; sleeves in which said axles are journaled; pivots for said axle-sleeves; rollers on said sleeves; ways for said rollers secured to said axle-frames; gears secured to said wheels; gears journaled on said 120 axle-pivots arranged to mesh with said gears on said wheels; a sectional driving-shaft; a compensating-gear driving connection for said shaft-sections; shafts arranged in suitable bearings on said axle-frames; gears thereon arranged to drive said gears on said 125 axle-pivots; compensating gears for connecting said driving-shaft sections to said shafts, carried by the axle-frames; tumbling-rods having universal-joint connections for connecting said compensating gears to the shafts carried by the forward axle-frames; a

- steering-rod connected to one of said axles; connections for the diagonally opposite axles; a pivoted bar; and links for connecting said bar to the forward axle, for the purpose specified.
22. The combination of the axle-frames; wheels; axles therefor; pivots on said axles; gears secured to said wheels; gears journaled on said axle-pivots, arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts, carried by the axle-frames; a steering-rod connected to one of said axles; connections for the diagonally opposite axles; a pivoted bar; and links for connecting said bar to the forward axle, for the purpose specified.
23. The combination of the axle-frames; wheels; axles therefor; pivots for said axles; gears secured to said wheels; gears journaled on said axle-pivots, arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts, carried by the axle-frames; tumbling-rods having universal-joint connections for connecting said compensating gears to the shafts carried by the forward axle-frames, for the purpose specified.
24. The combination of the axle-frames; wheels; axles therefor; pivots for said axles; gears secured to said wheels; gears journaled on said axle-pivots, arranged to mesh with said gears on said wheels; a sectional driving-shaft; a compensating-gear driving connection for said shaft-sections; shafts arranged in suitable bearings on said axle-frames; gears thereon arranged to drive said gears on said axle-pivots; compensating gears for connecting said driving-shaft sections to said shafts, carried by the axle-frames, for the purpose specified.
25. The combination of the axle-frames; wheels; axles therefor; pivots for said axles; gears secured to said wheels; gears journaled on said axle-pivots, arranged to mesh with said gears on said wheels; means for driving said gears; a steering-rod connected to one of said axles; connections for the diagonally opposite axles; a pivoted bar; and links for connecting said bar to the forward axle, for the purpose specified.
26. The combination of the axle-frames; wheels; axles therefor; pivots for said axles; gears secured to said wheels; gears journaled on said axle-pivots, arranged to mesh with said gears on said wheels; means for driving
- 1 said gears; a steering-rod connected to one of said axles; connections for the diagonally opposite axles; and equalizing connections for one pair of axles.
27. The combination of an axle-frame; 70 wheels; axles therefor; gears connected to the said wheels; gears carried by said axle-frame, arranged to mesh with said gears on said wheels, the axes of which coincide with the axes of the said axle-pivots; a sectional 75 driving-shaft; a compensating-gear driving connection for said driving-shaft sections; and compensating gears for connecting said driving-shaft sections to said gears carried by the said axle-frame, for the purpose specified. 80
28. The combination of an axle-frame; 85 wheels; axles therefor; gears connected to the said wheels; gears carried by said axle-frame, arranged to mesh with said gears on said wheels, the axes of which coincide with the axes of the said axle-pivots; a driving-shaft; and compensating gears for connecting said driving-shaft to said gears carried by the said axle-frame, for the purpose specified. 90
29. The combination of the axle-frames; a reach rigidly secured to said axle-frame; a pair of side-bars pivotally secured to said axle-frame; wheels; axles therefor; sleeves in which said axles are journaled; pivots for 95 said axle-sleeves; rollers on said axle-sleeves; yoke-like ways for said rollers, secured to said axle-frame; a steering-rod; a pinion thereon; a rack arranged to mesh with said pinion; a link connecting said rack to one of 100 the rear axle-sleeves; a pair of connecting-bars slidingly secured to said reach; links arranged to connect the diagonally opposite axles to said bars; a pivoted bar; and links connecting said pivoted bar to the forward 105 axles, all coacting for the purpose specified.
30. The combination of the axle-frames; a reach rigidly secured to said axle-frame; a pair of side-bars pivotally secured to said axle-frame; wheels; axles therefor; sleeves 110 in which said axles are journaled; pivots for said axle-sleeves; rollers on said axle-sleeves; ways for said rollers, secured to said axle-frame; a steering-rod connected to one of said axles; a pair of connecting-bars slidingly 115 secured to said reach; links arranged to connect the diagonally opposite axles to said bars; a pivoted bar; and links for connecting said pivoted bar to the forward axles, all coacting for the purpose specified. 120
31. The combination of the axle-frames; a reach rigidly secured to said axle-frame; a pair of side-bars pivotally secured to said axle-frame; wheels; axles therefor; sleeves in which said axles are journaled; pivots for 125 said axle-sleeves; rollers on said axle-sleeves; yoke-like ways for said rollers, secured to said axle-frame; a steering-rod; a pinion thereon; a rack arranged to mesh with said pinion; a link connecting said rack to one of the rear 130

axle-sleeves; connections for the diagonally opposite axles; a pivoted bar; and links for connecting said pivoted bar to the forward axles, all coacting for the purpose specified.

5 32. The combination of the axle-frames; a reach rigidly secured to said axle-frame; a pair of side-bars pivotally secured to said axle-frame; wheels; axles therefor; sleeves in which said axles are journaled; pivots for 10 said axle-sleeves; rollers on said axle-sleeves; ways for said rollers, secured to said axle-frame; a steering-rod connected to one of said axles; connections for the diagonally opposite axles; a pivoted bar; and links for 15 connecting said pivoted bar to the forward axles, all coacting for the purpose specified.

33. The combination of the axle-frames; wheels; axles therefor; pivots for said axles; a steering-rod; a pinion thereon; a rack arranged to mesh with said pinion; a link connecting said rack to one of the rear axle-sleeves; a pair of connecting-bars slidingly secured to said reach; links arranged to connect the diagonally opposite axles to said bars; a pivoted bar; and links for connecting said pivoted bar to the forward axles, all coacting for the purpose specified.

25 34. The combination of the axle-frames; wheels; axles therefor; pivots for said axles; 30 a steering-rod connected to one of said axles; a pair of connecting-bars slidingly secured to said reach; links arranged to connect the

diagonally opposite axles to said bars; a pivoted bar; and links for connecting said pivoted bar to the forward axles, all coacting for 35 the purpose specified.

35. The combination of the axle-frames; wheels; axles therefor; pivots for said axles; a steering-rod; a pinion thereon; a rack arranged to mesh with said pinion; a link connecting said rack to one of the rear axle-sleeves; connections for the diagonally opposite axles; a pivoted bar; and links for connecting said pivoted bar to the forward axles, all coacting for the purpose specified. 40

36. The combination of the axle-frames; wheels; axles therefor; pivots for said axles; a steering-rod connected to one of said axles; connections for the diagonally opposite axles; a pivoted bar; and links for connecting said 50 pivoted bar to the forward axles, all coacting for the purpose specified.

37. The combination of the axle-frames; wheels; axles therefor; pivots for said axles; rollers on said axles; ways for said rollers carried by said axle-frames; and connections for the diagonally opposite axles, for 55 the purpose specified.

In witness whereof I have hereunto set my hand in the presence of two witnesses.

CARSON DURKEE.

Witnesses:

E. MARIE JACKSON,
OTIS A. EARL.
